UNITED STATES PATENT OFFICE

150,516

DESIGN FOR A GAS COOKSTOVE

Herbert M. Reeves, Kankakee, Ill., and Montgomery Ferar, Detroit, Mich., assignors to Florence Stove Company, Gardner, Mass., a corporation of Massachusetts

Application April 11, 1947, Serial No. 138,314

Term of patent 7 years

(Cl. D81—4)

To all whom it may concern:

Be it known that we, Herbert M. Reeves and Montgomery Ferar, citizens of the United States, residing at Kankakee, in the county of Kankakee and State of Illinois, and Detroit, in the county of Wayne and State of Michigan, respectively, have invented a new, original, and ornamental Design for a Gas Cookstove, of which the following is a specification, reference being had to the accompanying drawing forming a part thereof.

The single figure of the drawing is a perspective view of a gas cookstove showing our new design, the end of the stove not shown being identical with that shown.

The dominant features of the design reside in the portions shown in full lines in the drawings.

We claim:

The ornamental design for a gas cookstove, substantially as shown and described.

HERBERT M. REEVES.
MONTGOMERY FERAR.
